UNITED STATES PATENT OFFICE.

GEORGE P. FARMER, OF MONTCLAIR, NEW JERSEY, ASSIGNOR TO THE CONSOLIDATED SAFETY PIN COMPANY, OF BLOOMFIELD, NEW JERSEY.

DESIGN FOR A PAPER-CLIP.

SPECIFICATION forming part of Design No. 30,946, dated June 6, 1899.

Application filed May 9, 1899. Serial No. 716,175. Term of patent 14 years.

To all whom it may concern:

Be it known that I, GEORGE P. FARMER, a citizen of the United States, residing in Montclair, Essex county, State of New Jersey, have invented and produced a certain new and original Design for Paper-Clips, of which the following is a specification, reference being had to the accompanying drawing, forming a part thereof.

This invention relates to clips of wire, such as are slipped upon the edges of sheets of paper or other material for the purpose of holding them together; and it consists in the design for such clips shown in the accompanying drawing, which illustrates in plan view a clip which embodies the design.

In accordance with the invention the clip comprises a middle loop with substantially

parallel members *a* and *b* and outer legs *c* and *d*, each of which is bent over toward the member *a* or *b*, from which it springs, as at *e*, and is then bent outwardly away from such member, as at *f*, the two portions forming in each outer leg an inward bend or knuckle *g*.

The characteristic feature of the design is the inward bend or knuckle of the outer legs.

I claim as my invention—

The design for a paper-clip, substantially as shown and described.

This specification signed and witnessed this 5th day of May, A. D. 1899.

GEORGE P. FARMER.

In presence of—

W. B. GREELEY,
L. R. MOORE.
